UNITED STATES PATENT OFFICE.

ALBERT SCHMID, OF HAVRE, FRANCE.

TRUCK-FRAME FOR MOTOR-CARS.

SPECIFICATION forming part of Letters Patent No. 710,809, dated October 7, 1902.

Application filed January 28, 1902. Serial No. 91,606. (No model.)

To all whom it may concern:

Be it known that I, ALBERT SCHMID, a citizen of the United States of America, residing at 3 Rue Vacquerie, St. Adresse, Havre, France, have invented certain new and useful Improvements in Truck-Frames of Motor-Cars, of which the following is a specification.

My invention relates to the construction of the truck-frame of a motor-car in such a manner that the passengers who occupy the body of the car are relieved from the shaking and vibration which attend the working of the motor, this construction also affording facilities in the building of motor-cars, the motor with the driving-gear and frame being separate from and independent of the car-body, so that the builder can make these parts separately, thereby greatly cheapening the building of motor-cars.

This invention also renders the motor, with its driving-gear, easy of access for inspection and repairs. For this purpose I construct the truck-frame, as I shall describe, referring to the accompanying drawings.

Figure 1 is a side view, and Fig. 2 is a plan, of a truck-frame according to my invention. Fig. 3 is a rear end view, and Fig. 4 is a front end view. Fig. 5 is a part side view, and Fig. 6 is an end view, showing a modification. Fig. 7 shows the car-body raised for making repairs on the motor or driving mechanism.

a is a main frame of rectangular form, having its rear carried on springs b, resting on the rear axle c, and having its front also carried on springs e, resting on the front axle f. The body of the car and the seats for passengers are carried on the main frame a, but the motor and driving-gear are carried on a separate frame, which consists of two side

bars g, which have eyes with adjustable bushes 40 embracing the rear axle c and which in front are carried on springs h, resting on the front axle f. The front wheels k are mounted on short crank-axes l, the crank-arms m of which are connected by a rod n, while another crank-arm p of one of the axles is connected by a rod q to steering-gear r.

Instead of the blade-springs h for carrying the front ends of the bars g helical springs s may be employed, as shown in Figs. 5 and 6. 50

As the side bars g, which carry the motor and driving-gear, are carried independently of the main frame a, the shake and vibration due to the motor are not transmitted to the body of the car, which can be made while the truck-frame with the motor and driving-gear can be separately prepared, the whole being finally put together to complete the car.

Having thus described the nature of this invention and the best means I know of carrying the same into practical effect, I claim—

A motor-car having a truck-frame made in two separate and independent parts, independently mounted, one of said parts carrying the motor and driving-gear, the other 65 part carrying the car-body and being hinged on one of the truck-axles and arranged to be swung upwardly to give access to the driving mechanism, said body when lowered resting on springs on the front and rear axles; substantially as described.

In testimony whereof I have hereunto set my hand in presence of two subscribing witnesses.

ALBERT SCHMID.

Witnesses:

JULES FRIEDMAN,
E. J. MORCKERBAKER.
